CLAIM

I claim the ornamental design for a camera module, as shown and described.

DESCRIPTION

FIG. 1 is a perspective view of a camera module showing our new design;

FIG. 2 is a front view of the camera module of FIG. 1;

FIG. 3 is a back view of the camera module of FIG. 1;

FIG. 4 is a left side view of the camera module of FIG. 1;

FIG. 5 is a right side view of the camera module of FIG. 1;

FIG. 6 is a top view of the camera module of FIG. 1; and,

FIG. 7 is a bottom view of the camera module of FIG. 1.

The broken lines in the drawings are directed to environment, and form no part of the claimed design.
